UNITED STATES PATENT OFFICE

2,467,931

TIE FORM

Leonard D. Davidson, Chicago, Ill.

Application October 11, 1946, Serial No. 702,796

19 Claims. (Cl. 223—65)

1

This invention relates to an improved tie form for shaping neckties, and relates particularly to an improved form for holding an end of a tie.

The present invention is an improvement over the Charles Park Green Patent No. 2,038,786, which also relates to a tie form. This patent shows a tie form comprising a yoke shaped resilient member including a pair of prongs adapted to be readily insertable into a necktie with the prongs pressing yieldably outwardly against the opposite edges of the tie to hold it stretched and facilitate cleaning and drying the tie. There is also included a member permanently mounted on the bight of the yoke having resilient arms to press and hold the sides of the tie adjacent the end against the prongs. Means are included, also permanently mounted on the bight, for grasping and holding the tip of the tie. The present invention is an improvement over this structure in that this invention comprises a unit mounted on the bight of the yoke and readily removable therefrom, with the unit including a holding means for holding the tip of the tie in stretched position. In some embodiments of the present invention the arms that clasp the side edges of the tie against the prongs are removable as a unit together with a means for holding the extreme tip that is also removable. In others the pressing arms are mounted on the bight with the holding means for the tip of the tie only being removable. It has been found that the present invention is an improvement over that set out in the Green patent, as it permits easier construction of the tie form, and is easier to use. The new tie form is also easier to assemble.

One of the features of this invention is the provision of a separate and removable unit adapted to be mounted on the bight of the yoke that keeps the tie stretched, with the unit including means for holding the extreme tip of the tie; another feature of the invention is the provision of a unit that is separate and removable from the bight for holding an end of the tie and the extreme tip; and a further feature is the provision of a one-piece unit that is easily applied to and removed from the bight of the yoke, with this unit serving to hold the end of the tie including the extreme tip. Some of these features apply to all embodiments of the invention, while others apply only to one or more embodiments. Other features and advantages will be apparent in the detailed description of the invention given hereinafter.

The invention is described as related to the embodiments shown in the accompanying draw-

2

ings. Of the drawings Fig. 1 is an elevation of one embodiment of the invention applied to a tie; Fig. 2 is an enlarged fragmentary elevation showing the bottom of the holding and stretching member together with means for holding the extreme tip of the tie; Fig. 3 is a vertical section taken along line 3—3 of Fig. 2; Fig. 4 is an elevation showing the holding device separate from the stretching means; Fig. 5 is a horizontal section taken along line 5—5 of Fig. 2; Fig. 6 is an elevation similar to Fig. 2 showing a second embodiment of the invention; Fig. 7 is an elevation similar to Fig. 6 but showing the other side of the holding unit; Fig. 8 is a vertical section taken along line 8—8 of Fig. 6; Fig. 9 is a horizontal section taken along line 9—9 of Fig. 6; Fig. 10 is a view similar to Fig. 2 showing a third embodiment of the invention; Fig. 11 is an elevation similar to Fig. 10 showing the other side of the device; and Fig. 12 is a vertical section taken along line 12—12 of Fig. 10.

In the embodiment shown in Figs. 1 to 5 inclusive there is shown a yoke-shaped unit 20 having two prongs 21 adapted to be inserted into the large end of the tie 22. A similarly shaped yoke 23 has prongs 24 adapted to be inserted in the small end of the tie. Each yoke has a bight 25, and the prongs and bight are made of a continuous piece of relatively heavy wire. The ends 26 of the prongs 21 are bent toward each other so as to aid in inserting the prongs into the end of the tie. The prongs 24 have similarly shaped ends 27. Each pair of prongs are adapted to press outwardly away from each other and stretch the tie.

The unit for holding the end of the tie is made of resilient sheet material such as metal and includes a portion 29 passing around the bight 25, a tip holding portion 28, resilient arms 30 having curved ends 31 shaped to pass around the outer surfaces of the prongs 21 and hold the tie against the prongs. The arms 30 are normally closer together when they are free of the prongs than they are when they are around the prongs. Thus the natural resiliency of the arms causes them to bear against the sides of the tie and hold these sides against the prongs. The two arms 30 come together at their lower ends and are held by means of a collar 32. There is a strip 33 of metal between the lower ends of the arms 30 and the tip holding portion 29. This strip 33 has a sharp pointed hook 34 on its inner side for piercing the tip 35 of the tie. On the other side of the tip holding portion 28 there is an upward extension 36 of the sheet metal strip, with this extension

being adjacent the hook 34. At the top of this extension is a downward extension 37. The upward extension 36 has a second hook 38 therein located below the first hook and also adapted to pierce the tip 35 of the tie. The extreme tip is adapted to be held within the tip holding portion 28.

The entire holding unit that is adapted to be supported on the bight 25 may conveniently be made from a single piece of sheet metal. The extensions 37 and 36, the bight encircling portion 29, the tip holding portion 28, and the intermediate strip 33 are all the same width as the full width of the strip of metal, and are formed by bending the strip to the required shape. The top of the intermediate portion 33 is bent as shown in Figs. 3 and 4 so that the remainder of the strip is doubled. The strip is then split down the center to the top of the intermediate portion 33, to make the arms 30. The inner end of this split portion is held by the collar 32. The outer ends of the arms 30 may then be bent to form the curved ends 31 that hold the sides of the tie against the prongs 21.

In using the tie form the prongs 21 are inserted into their end of the tie. The holding unit is then placed in position on the bight, and the arms 30 are arranged so that their curved ends 31 are around the prongs and press the edges of the tie against the prongs. The extending portion 37 is used to separate the hooks 34 and 38, and the tip 35 of the tie is inserted between the hooks. The tip of the tie may be grasped and stretched before the hooks pierce the fabric, thus insuring complete stretching of the tie. The complete form serves to stretch the end of the tie including the extreme tip between the bight 25 and the prongs 21, and insures the proper shape of the tie during cleaning and drying.

In forming the unit for holding the end of the tie it is advisable to provide a small hole 39 at the base of the arms 30. This enables the sheet metal used in making the unit to be more easily bent and lessens the danger of splitting the metal due to a concentration of strains around the base of the arms.

The hooks 34 and 38 may be held in engagement with the tip of the tie by the resiliency of the metal, or the ends of the hooks may engage small holes located in the unit opposite the hooks.

In the embodiment shown in Figs. 6 to 9 inclusive the holding unit is made of wire that is folded at 40 to make two substantially equal lengths and twisted at a point 41 intermediate the fold 40 and the ends of the wire. The free ends beyond the twist form the arms 42. The end of each arm 42 is bent to form a curved portion 43 which surrounds a prong 21 to hold the edge of the tie tightly against the prong. The fold 40 is bent back upon the wire to form bight encircling portions 44. The fold 40 presses against the body of the wire beneath the twist 41, and serves as a spring to hold the extreme tip 35 of the tie. Thus the sides of the tie and the tip are held by the natural resiliency of the wire.

In the embodiment shown in Figs. 10, 11, and 12 the wire 45 is wound around the bight 25a to form loops 46 encircling the bight. The wire is wound at its mid-portion to form the arms 47. These arms have curved ends 48 to press against the prongs 21a with the pressing action being caused by the resiliency of the arms 47. The curved portions 48 serve to hold the sides of

the tie against the prongs 21a. A separate and removable hook member 49 is provided to hold the extreme point 35 of the tie. This hook member has one end 50 partially encircling an arm 47, and then passes down around the loops 46 and up to a point above the extreme tip of the tie. This last portion has a downwardly directed hooked end 51 for piercing the tip 35 of the tie and holding the tie stretched between the prongs 21a and bight 25a. The hook member may be easily applied to and removed from the tie form.

Although all embodiments of the invention shown in the drawings employ removable holding members attachable to the bight of the tie form for holding the side portions of the tie at the end, this is not actually necessary in all cases. Removable means may be provided for engaging the end of the tie without engaging the bight of the form. In such a construction the holding member might engage only the tie covered prongs and, where desired, extend inwardly to engage the tip of the tie.

Having described my invention as related to the embodiments shown in the accompanying drawings, it is my intention that the invention be not limited by any of the details of description unless otherwise specified, but rather be construed broadly within its spirit and scope as set out in the accompanying claims.

30 I claim:

1. In a tie form comprising a yoke shaped resilient member having a pair of prongs insertable into the end of a tie with the prongs pressing yieldably outwardly against the opposite edges of the tie to hold it stretched, means comprising a unit readily mountable on and removable from the form for holding the end of the tie that is opposite said prongs in stretched position on said form.

40 2. In a tie form comprising a yoke shaped resilient member having a pair of prongs insertable into the end of a tie with the prongs pressing yieldably outwardly against the opposite edges of the tie to hold it stretched, means for holding 45 the end of the tie comprising a unit mounted on the bight of the yoke and readily removable therefrom with said unit including a holding means for holding the tip of the tie that is opposite said prongs in stretched position between said prongs and said bight.

3. In a tie form comprising a yoke shaped resilient member having a pair of prongs insertable into the end of a tie with the prongs pressing yieldably outwardly against the opposite edges of the tie to hold it stretched, means for holding the end of the tie comprising a unit mounted on the bight of the yoke and readily removable therefrom with said unit including a wire hook means for piercing the tip of the tie that is opposite said prongs and holding said tip in stretched position between said prongs and said bight.

4. In a tie form comprising a yoke shaped resilient member having a pair of prongs insertable into the end of a tie with the prongs pressing yieldably outwardly against the opposite edges of the tie to hold it stretched, means for holding the end of the tie comprising a unit mounted on the bight of the yoke and readily removable therefrom with said unit including a sheet metal hook means for piercing the tip of the tie that is opposite said prongs and holding said tip in stretched position between said prongs and said bight.

5. In a tie form comprising a yoke shaped resil-

ient member having a pair of prongs insertable into the end of a tie with the prongs pressing yieldably outwardly against the opposite edges of the tie to hold it stretched, means for holding the end of the tie comprising a unit mounted on the bight of the yoke and readily removable therefrom with said unit including a friction means for grasping the tip of the tie that is opposite said prongs and holding it in stretched position between said prongs and said bight.

6. In a tie form comprising a yoke shaped resilient member having a pair of prongs insertable into the end of the tie with the prongs pressing yieldably outwardly against the opposite edges of the tie to hold it stretched, a unit for holding the end of the tie comprising a member to be mounted on the bight of the yoke having resilient means to press the side edges of the tie against the prongs and a holding means to hold the tip of the tie in stretched position between said prongs and said bight, said unit being readily applied to and removed from said bight.

7. In a tie form comprising a yoke shaped resilient member having a pair of prongs insertable into the end of the tie with the prongs pressing yieldably outwardly against the opposite edges of the tie to hold it stretched, a unit for holding the end of the tie comprising a member to be mounted on the bight of the yoke having resilient means to press the side edges of the tie against the prongs and a holding means to hold the tip of the tie in stretched position between said prongs and said bight, said unit being made of sheet metal and being readily applied to and removed from said bight.

8. In a tie form comprising a yoke shaped resilient member having a pair of prongs insertable into the end of the tie with the prongs pressing yieldably outwardly against the opposite edges of the tie to hold it stretched, a unit for holding the end of the tie comprising a sheet metal member to be mounted on the bight of the yoke having resilient sheet metal arms to press against the prongs and hold the side edges of the tie and hook means to pierce the tip of the tie and hold the tip in stretched position between said prongs and said bight, said unit being readily applied to and removed from said bight.

9. In a tie form comprising a yoke shaped resilient member having a pair of prongs insertable into the end of the tie with the prongs pressing yieldably outwardly against the opposite edges of the tie to hold it stretched, a unit for holding the end of the tie comprising a sheet metal member to be mounted on the bight of the yoke having resilient sheet metal arms to press against the prongs and hold the side edges of the tie and hook means to pierce the tip of the tie and hold the tip in stretched position between said prongs and said bight, said unit being readily applied to and removed from said bight, and said unit being held on the bight by the resiliency of the sheet metal.

10. In a tie form comprising a yoke shaped resilient member having a pair of prongs insertable into the end of the tie with the prongs pressing yieldably outwardly against the opposite edges of the tie to hold it stretched, a removable unit for holding the end of the tie comprising: a sheet metal member having a spring base portion adapted to grasp the bight of the yoke; a pair of resilient arms extending from the base portion normally urged toward each other by their resiliency and having means at their ends to press against the prongs and hold the side edges

of the tie; and hook means adjacent that portion of the unit contacting the bight adapted to pierce the tip of the tie and hold the tip in stretched position between said prongs and said bight.

11. A tie form unit as set forth in claim 10 wherein the pressing means at the end of each arm comprises a curved portion of the arm adapted to press against a side edge of the tie and hold it against the corresponding prong.

12. In a tie form comprising a yoke shaped resilient member having a pair of prongs insertable into the end of the tie with the prongs pressing yieldably outwardly against the opposite edges of the tie to hold it stretched, a removable unit holding the end of the tie comprising: a sheet metal member having a spring base portion adapted to grasp the bight of the yoke; a pair of resilient arms extending from the base portion normally urged toward each other by their resiliency and having means at their ends to press against the prongs and hold the side edges of the tie; and hook means adjacent that portion of the unit contacting the bight adapted to pierce the tip of the tie and hold the tip in stretched position between said prongs and said bight, said hook means being formed of a wedge shaped portion of metal cut away from and displaced outwardly from the sheet metal.

13. In a tie form comprising a yoke shaped resilient member having a pair of prongs insertable into the end of the tie with the prongs pressing yieldably outwardly against the opposite edges of the tie to hold it stretched, a removable unit for holding the end of the tie comprising: a sheet metal member having a spring base portion adapted to grasp the bight of the yoke; a pair of resilient arms extending from the base portion normally urged toward each other by their resiliency and having means at their ends to press against the prongs and hold the side edges of the tie; and an extended end portion adjacent the base portion for aid in grasping the unit in applying it to and removing it from said bight.

14. In a tie form comprising a yoke shaped resilient member having a pair of prongs insertable into the end of the tie with the prongs pressing yieldably outwardly against the opposite edges of the tie to hold it stretched, a unit for holding the end of the tie comprising a member to be mounted on the bight of the yoke having resilient means to press the side edges of the tie against the prongs and a holding means to hold the tip of the tie in stretched position between said prongs and said bight, said unit being made of wire and being readily applied to and removed from said bight.

15. In a tie form comprising a yoke shaped resilient member having a pair of prongs insertable into the end of the tie with the prongs pressing yieldably outwardly against the opposite edges of the tie to hold it stretched, a unit for holding the end of the tie made from a continuous piece of wire and comprising: a base portion adapted to pass around the bight of the yoke; a pair of resilient arms extending from the base portion normally urged toward each other by their resiliency and having means at their ends to press against the prongs and hold the side edges of the tie; and holding means adjacent that part of the base portion adapted to pass around the bight for holding the tip in stretched position between said prongs and said bight.

16. In a tie form comprising a yoke-shaped resilient member having a pair of prongs inserta-

ble into the end of the tie with the prongs pressing yieldably outwardly against the opposite edges of the tie to hold it stretched, a unit for holding the end of the tie made from a continuous piece of wire and comprising: a base portion adapted to pass around the bight of the yoke and having an end extending upwardly in a plane approximately parallel to the remainder of the unit; and a forked portion having a pair of resilient arms extending from the other side of the base portion normally urged toward each other by their resiliency and having means at their ends to press against the prongs and hold the side edges of the tie, said extending end being pressed against the base of said fork to grasp and hold the extreme tip of the tie in stretched position between said prongs and said bight.

17. In a tie form comprising a yoke shaped resilient member having a pair of prongs insertable into the end of the tie with the prongs pressing yieldably outwardly against the opposite edges of the tie to hold it stretched, a unit for holding the end of the tie comprising: a resilient wire wound around the bight of the yoke and having its two ends in approximately the same plane with the ends forming arms normally urged toward each other by their resiliency; means on the ends of the arms to press against the prongs and hold the side edges of the tie; and a separate removable member adapted to extend from the bight and hold the extreme tip of the tie in fully extended position.

18. In a tie form comprising a yoke shaped resilient member having a pair of prongs insertable into the end of the tie with the prongs pressing yieldably outwardly against the opposite edges of the tie to hold it stretched, a unit for holding the end of the tie comprising: a resilient wire wound around the bight of the yoke and having its two ends in approximately the same plane with the ends forming arms normally urged toward

each other by their resiliency; means on the ends of the arms to press against the prongs and hold the side edges of the tie; and a separate removable member adapted to extend from the bight and having a hook to pierce the extreme tip of the tie and hold it in fully extended position.

19. In a tie form comprising a yoke shaped resilient member having a pair of prongs insertable into the end of the tie with the prongs pressing yieldably outwardly against the opposite edges of the tie to hold it stretched, a unit for holding the end of the tie comprising: a resilient wire wound around the bight of the yoke and having its two ends in approximately the same plane with the ends forming arms normally urged toward each other by their resiliency; means on the ends of the arms to press against the prongs and hold the side edges of the tie; and a separate removable wire member adapted to grasp one arm, extend down around that portion of the unit surrounding the bight, and up to a hook formed in the end of the member with the hook being adapted to pierce the extreme tip of the tie and hold it in fully extended position.
